(57) **CLAIM**

The ornamental design for an combination HDMI interface with converter, as shown and described.

DESCRIPTION

FIG. 1 is a perspective view of a combination HDMI interface with converter, showing my new design wherein the converter is shown separately for clarity of disclosure;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the combination HDMI interface with converter, showing my new design wherein the HDMI interface is shown separately for clarity of disclosure;

FIG. 10 is another perspective view thereof;

FIG. 11 is a rear elevational view thereof;

FIG. 12 is a front elevational view thereof;

FIG. 13 is a right side elevational view thereof;

FIG. 14 is a left side elevational view thereof;

FIG. 15 is a top plan view thereof;

FIG. 16 is a bottom plan view thereof;

FIG. 17 is a perspective view of the combination HDMI interface with converter, showing my new design;

FIG. 18 is an enlarged view of portion 18 shown in FIG. 9; and,

FIG. 19 is an enlarged view of portion 19 shown in FIG. 10. The dash-dash broken lines in the drawings depict portions of the combination HDMI interface with converter that form no part of the claimed design. The dot-dash broken lines are imaginary lines that are included for reference purposes only to identify the enlarged views and form no part of the claimed design.
